CLAIM

The ornamental design for an electric vehicle charging totem with display screen as shown and described.

DESCRIPTION

FIG. 1 is a left front perspective view showing the ornamental design of the claimed electric vehicle charging totem with display screen;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof; and,

FIG. 8 is a left front perspective view thereof.

In FIGS. 1 to 8 the dash-dash broken lines are for the purpose of illustrating portions of the electric vehicle charging totem with display screen that form no part of the claimed design.

1 Claim, 7 Drawing Sheets
